UNITED STATES PATENT OFFICE.

JOHN R. MITCHELL, OF CHICAGO, ILLINOIS, ASSIGNOR TO W. H. MINER, OF CHICAGO,
ILLINOIS.

RAILWAY DRAFT-RIGGING.

1,140,523.

Specification of Letters Patent. Patented May 25, 1915.

Application filed September 28, 1911, Serial No. 651,719. Renewed August 12, 1914. Serial No. 856,489.

To all whom it may concern:

Be it known that I, JOHN R. MITCHELL, a citizen of the United States, residing at Chicago, in the county of Cook and State of Illinois, have invented a certain new and useful Improvement in Railway Draft-Rigging, of which the following is a full, clear, concise, and exact description, reference being had to the accompanying drawings, 10 forming a part of this specification.

My invention relates to an improvement in draft rigging for railway cars.

One of the objects of my invention is to promote the safety of railway employees by 15 providing a railway draft rigging in which an increased space between the railroad cars to which it is applied may be obtained.

My invention is of such a nature that it permits the use of the present equipment 20 and so rearranges the present equipment that this additional space is provided. In one form of application of my invention to certain kinds of cars I use a draw bar or coupler shank of the usual length and do not 25 change the place of attachment of the railway draft rigging to the frame of the railroad car.

My invention is fully described in the specification and shown in the accompanying drawings, in which—

Figure 1 is a side elevation of a portion of a draft rigging embodying my invention. Fig. 2 is a top plan of a yoke and coupler and other parts. Fig. 3 is a vertical longitudinal section of an extension block on line 3—3 of Fig. 4. Fig. 4 is a horizontal section of an extension block on line 4—4 of Fig. 3. Fig. 5 is a vertical longitudinal section on line 5—5 of Fig. 6. Fig. 6 is a part top plan and part horizontal sectional view of the modification shown in Fig. 5.

Referring to the drawings, 8 is a yoke of ordinary form.

10 is a coupler shank or draw bar of ordinary length, which may be provided with an ordinary coupler head, 9, and the rear end or butt of which coupler shank extends into an extension block, 11, preferably made integral with the block-like casting, 13, 50 which is preferably made hollow, as indicated in Figs. 3 and 4 at the numerals 14, and provided in its preferably hollow form with reinforcing collars, 15, at its top and bottom, the said casting being perforated vertically with openings, 17, to receive the

means, preferably rivets, 16, which attach the same to the yoke, 8. The coupler shank, 10, is provided near its rear end with a transverse slot, 18, into which securely fits the removable coupler key, 19. The side 60 plates, 12, are provided with slots, 20, also through which the coupler key, 19, passes. The coupler shank, 10, abuts at its rear end against the front face, 21, of the block-like casting, 13, and is held in place by means of 65 the said removable key, 19, passing through the side plates, 12. The extension block, 11, is preferably made with its forwardly extending side plates, 12, narrower vertically than the block-like end of said extension 70 block, so as to provide shoulders, 22, into which the gibs, 23, of the yoke, 8, fit.

Fig. 5 is a modification of the extension block in which the side plates, 12, are of a greater vertical width than the block-like 75 portion, 13, of the extension block, to receive the rear end of a coupler shank, of comparatively greater dimensions and also illustrates a modification in which the side plates, 12, may be joined at either top or bottom by 80 integral plates or joined at both top and bottom by integral top and bottom plates, 25, 26, thus forming a hollow box-like head, 27, projecting forwardly from the block-like 85 part 13 of the extension block, 11, to receive 90 the coupler shank, 10. The upper plate 25 or lower plate 26 may be provided at its forward edge with a transverse flange or gib, 28, to engage with the forward shoulder, 29, of the butt of the coupler shank, 10.

To increase the space between the cars of a train without changing the place of attachment of the railway draft rigging to the frame work of the railroad car and using a draw bar of usual length, the extension 95 block, 11, is attached to the ordinary yoke, 8, preferably by rivets, 16, being in the same manner usually employed to attach the coupler shank to the yoke. The coupler shank, 10, is then inserted into the forward part of 100 the extension block, 11, between its side plates 12 and attached to the extension block by means of the key, 19; thus the coupler head, 9, is extended forwardly from the position in which it is found when the coupler shank is attached at its rear end directly to the yoke, 8. The modification in which the extension block is shown in Figs. 105 5 and 6 provided with a hollow box-like head with a gib extending from the upper 110

plate thereof may be employed in the same manner. This form of construction adds security in the attachment of the coupler shank to the extension block and also permits the coupler to be easily removed and replaced.

I realize that considerable variation is possible in the construction herein described without departing from the spirit of my invention and therefore by the foregoing accurate description I do not intend to be limited thereto, except as pointed out in the following claims:

1. In a railway draft rigging, in combination, a draw-bar, a draft yoke forwardly provided with inturned gibs, an extension block secured between the limbs of the yoke

having shoulders engaging said gibs, said extension block being provided with forwardly extended lateral plates spaced apart to receive the draw-bar, the rear face of the draw-bar abutting the gibs of the yoke.

2. In a railway draft rigging, in combination, a U-shaped draft yoke, a draw-bar abutting against the free ends thereof, an extension block secured between the limbs of the yoke, a key, forward slotted extensions from said block spaced apart to receive the draw-bar, the key passing through the said extensions and draw-bar.

JOHN R. MITCHELL.
